(57) **CLAIM**

The ornamental design for a controller for therapy device, as shown and described.

DESCRIPTION

FIG. 1 illustrates a top perspective view of a controller for therapy device;

FIG. 2 illustrates a front view of the controller for therapy device thereof;

FIG. 3 illustrates a back view of the controller for therapy device thereof;

FIG. 4 illustrates a left side view of the controller for therapy device thereof;

FIG. 5 illustrates a right side view of the controller for therapy device thereof;

FIG. 6 illustrates a top view of the controller for therapy device thereof;

FIG. 7 illustrates a bottom view of the controller for therapy device thereof;

FIG. 8 illustrates a bottom perspective view of the controller for therapy device thereof; and,

FIG. 9 illustrates an environmental view of the controller for therapy device thereof.

The broken lines shown in the drawings are included for illustration purposes only and form no part of the claimed design.

1 Claim, 9 Drawing Sheets
